[57] CLAIM

[21] Appl. No.: 791,565

The ornamental design for a card and playing piece holder for a game, as shown and described.

[22] Filed: Oct. 25, 1985

DESCRIPTION

[30] Foreign Application Priority Data

FIG. 1 is an elevational view showing the right side of a card and playing piece holder embodying our design.
FIG. 2 is a plan view showing the top of our design.
FIG. 3 is a perspective view showing the top, left side and front of our design, the back being similar to the front and the bottom being plain and unornamented.
